[57] CLAIM

The ornamental design for a capo for a stringed musical instrument, as shown and described.

DESCRIPTION

FIG. 1 is a top perspective view of a capo for a stringed musical instrument showing our new design; FIG. 2 is a side elevational view, opposite to that shown in FIG. 1;

FIG. 3 is a left end view;

FIG. 4 is a right end view; and

FIG. 5 is a bottom view, the attaching element being broken away for clarity of illustration.
